mesne assignments, to Sylvania Electric Products Inc.,
Wilmington, Del., a corporation of Delaware

Application August 19, 1957, Serial No. 678,892

8 Claims. (Cl. 315—3.6)

This invention relates to electron tubes of the traveling-wave type. It provides novel electron tubes, especially useful for amplifying electric signals over broad frequency ranges at microwave frequencies, that have higher efficiencies and greater output power capabilities than those obtainable with conventional traveling-wave tubes. Relatively small size, freedom from backward-wave interaction and other advantages are also achieved while the basic advantages of traveling-wave operation are retained.

The amount of output microwave power that can be obtained from a conventional traveling-wave tube amplifier is limited by several factors that are well known to those skilled in the art. Conventional traveling-wave tubes require a long electron beam of small cross-sectional area. In such a tube, sufficient beam current for a large power output would necessitate very high current densities in the electron beam. Thus, a very high rate of electron emission from a small cathode area is needed. Even with heavy magnets it is hard to keep a long, high-density electron beam focused into a cylinder of small cross-sectional area. The mutual repulsion between electrons in a beam having high space-charge densities produces powerful forces tending to spread the beam. If electro-magnets are used for beam focusing the considerable power consumed by the magnets further reduces the already low over-all efficiency of the amplifier.

At the higher microwave frequencies the solution of these problems becomes increasingly difficult in conventional traveling-wave tubes because the necessary smallness at such frequencies of the helix (or other slow-wave structure) limits the permissible cross-sectional area of the electron beam to very small values. Backward-wave interaction in the tube further limits the permissible maximum helix diameter and therefore limits the permissible cross-sectional area of the electron beam, even in cases where a hollow cylindrical beam outside the helix is employed. In conventional traveling-wave tubes designed for operation in the higher microwave frequency ranges the helix diameter and the cross-sectional area of the electron beam become quite small.

Not only the power output but also the frequency response of the amplifier suffers as a consequence of the small helix diameters required in conventional traveling-wave tubes for operation in the higher frequency ranges. This is because a helix becomes dispersive as its diameter is made small—that is, the phase velocity of electromagnetic waves transmitted along the helix varies as a function of frequency, so that interaction with the electron beam can be maintained over only a relatively narrow band of frequencies for any given beam velocity. Similarly, the use of dispersive filter-type circuits and the like in place of helices as slow-wave structures, in an attempt to achieve higher efficiencies and to overcome other difficulties, narrows the frequency bandwidth.

Even if all of the foregoing difficulties were solved the efficiency of the conventional traveling-wave tube would

remain low when operated under conditions appropriate to broad-band signal amplification. Reasons for this low efficiency need not be explored for an understanding of the present invention. However, it can be noted that a large portion of the long electron beam in a conventional traveling-wave tube interacts with a relatively weak RF field and therefore a large portion of the RF field is not strong enough to extract a considerable percentage of the kinetic energy from the beam. A strong RF field, capable of producing large changes in the electron velocities, exists only in a relatively short section near the output end of the slow-wave structure and even here over-bunching of the beam, saturation effects, and other factors may limit the amount of energy that can be transferred to the RF field. The remaining kinetic energy of the electron beam is converted into heat when the electrons strike the collector electrode and other parts of the tube. Not only is this energy wasted, with consequent low efficiency of the amplifier, but also the heat must be removed from the tube. In typical cases the energy so wasted is several times larger than the energy transferred from the electron beam to the RF field. The use of RF attenuators, necessary in a conventional traveling-wave tube to prevent undesirable oscillations, further lowers the efficiency.

Heretofore, extensive efforts by many workers in the art to solve the foregoing and other problems have resulted in the proposal and evolution of many ingenious amplifier tubes of various types and of mixed types, too numerous to describe here. In general, tubes known to the prior art for amplifying signals at high microwave frequencies either are inefficient and incapable of high power output or are relatively narrow-band amplifiers. Some of the prior art proposals that initially appeared to be promising have failed in practice to yield any useful power gain.

Briefly stated, in accordance with certain aspects of this invention, a new type of electron tube, for amplifying electric signals at microwave frequencies, has parallel input and output wave-transmission structures each adapted to transmit electromagnetic waves from one to the other of its two ends. In a preferred embodiment the two wave-transmission structures are two electrically conductive helices extending parallel to each other. These two helices are appropriately called the input helix and the output helix. Input electric signals are supplied to input terminals at one end of the input helix and travel along the length of the input helix with velocities determined chiefly by the helix geometry according to principles that are well-known to those skilled in the art. Electromagnetic waves induced in the output helix, in a manner hereinafter described, travel in the same direction at the same velocity along the output helix and provide an amplified output signal at output terminals connected to the other end of the output helix. In other words, the two helices constitute parallel input and output slow-wave structures.

An electron stream, provided by suitable electron gun means, flows closely across the input and output helices in sequence, in interacting relation to the electromagnetic waves transmitted thereby. The waves transmitted by the input helix velocity-modulate the electron stream, and the modulated stream supplies energy to waves transmitted by the output helix, so that the waves on the output helix progressively increase in energy as they travel toward the output terminals of the tube.

A transverse dimension of the electron stream extends for a considerable distance (many wavelengths) along the length of each helix so that different transverse portions of the electron stream are modulated by waves on different lengthwise segments of the input helix with different instantaneous phase angles. Consequently, the

waves induced upon different lengthwise segments of the output helix by the modulated electron stream likewise have different instantaneous phase angles. However, since the waves transmitted in a forward direction on both helices travel in the same direction at substantially the same velocity, all of the wave components induced on the output helix arrive at the output terminals of the tube in additive phase relation.

In other words, electromagnetic wave components traveling in the forward direction on the output helix are reinforced and progressively increased energy-wise by additional induced wave components in each lengthwise portion of the output helix. Therefore, a growing wave travels along the output helix toward the output terminals of the tube. On the other hand, any wave components that may travel in a backward direction (away from the output terminals) along the output helix are somewhat out-of-phase with the wave components induced in successive lengthwise segments of the output helix, and are progressively attenuated. Consequently, this type of backward-wave interaction is no problem in the new tubes. Other types of backward-wave interaction likewise present no problem, for reasons hereinafter discussed.

In a preferred embodiment the electron stream has the form of a planar sheet of moving electrons, produced by an electron gun comprising an elongated strip cathode and focusing electrode; or, two such sheets of electrons may be employed, substantially parallel to each other, passing across opposite sides of the two helices. In other cases, the sheets of electrons may each be divided into a plurality of parallel electron beams produced, for example, by a plurality of electron guns having small-area cathodes.

In the description thus far, interaction between the electron stream and the traveling electromagnetic waves has been assumed without specifying the mechanism whereby adequate interaction is accomplished. This is a crucial point at which certain prior art proposals have failed. If the amount of interaction is too small the tube will not yield a useful microwave power gain.

In tubes constructed according to the present invention, interaction between the electron stream and the traveling electromagnetic waves takes place in a manner somewhat analogous to the interaction principle of conventional traveling-wave tubes. That is, each of the two wave-transmitting structures is a slow-wave structure adapted to transmit electromagnetic waves having at least one wave component with a phase velocity that is small compared to the velocity of light. A conductive helix is a well-known example of such a slow-wave structure. The direction and velocity of electron flow in the electron stream is so chosen that the electron flow has a velocity component in the direction of said phase velocity and at approximately the same speed so that electrons passing through the RF field of the transmitted waves remain in approximately constant phase-positional relation to said wave component over a distance larger than a microwave wavelength, preferably several wavelengths, of the slow-wave component. Thus, a reasonably long interaction time is provided. That is, each interacting electron, on the average, remains in interacting relation to the electromagnetic waves on each helix for several microwave cycles.

In a preferred embodiment of this invention the desired phase-positional relationship is accomplished by directing a transverse electron stream at an acute angle to the longitudinal axial direction of the parallel input and output helices (but usually not intersecting the helix axes) so that the electron flow has a velocity component in a direction of low-velocity electromagnetic wave propagation on both helices. This velocity component is made approximately equal to and slightly greater than the slow-wave velocity in the same direction by adjustments herein described, to establish and maintain the well-known

phase-positional relation required for interactions of the traveling-wave amplifier type.

Preferably, the two helices are flattened in a plane parallel to the electron stream (as viewed from one end, each helix has a "race-track" shape) so that the electron stream can pass close to a large portion of the flattened cylindrical surface of the helix. Thus, the electron stream travels for a considerable distance (several wavelengths) in close proximity to each helix, and therefore in relatively strong portions of the RF field associated with each of the transmitted electromagnetic waves. Consequently, a fairly strong interaction of the traveling-wave amplifier type is achieved between the electron stream and the electromagnetic waves transmitted by each of the two helices.

The interaction so obtained differs greatly from the interaction produced by directing an electron stream across a single interaction gap in klystron-like structures and simple slotted waveguides, not only quantitatively but also in basic principles and consequences of fundamental importance to the operation of the amplifier as a whole.

In fact, each of the two wave-transmission structures, in association with the electron stream, is in itself, without regard to the other wave-transmission structure, a traveling-wave "amplifier" having a low power gain, preferably unity power gain. While such a structure, standing alone, may not produce a useful power gain, the two structures and the electron stream in combination, according to the principles herein disclosed, can yield large power gains and supply a large microwave power output at considerably higher efficiencies than have been realized with prior broad-band amplifiers at high microwave frequencies.

The electron paths in the new tubes are usually shorter than in conventional traveling-wave tubes. More important, the cross-sectional area of the electron streams in the new tubes is relatively large so that large electron currents can be obtained without resort to extremely high current densities. Consequently, the space-charge density in the electron stream is relatively low; and this fact, in combination with the shortness of the electron paths, makes it easy to solve the beam-focusing problem. Also, the electron gun construction is simplified in certain respects since a large-area cathode is feasible and extremely high rates of electron emission from small cathode areas are not required. Furthermore, the elimination of backward-wave interaction problems makes possible the use of larger helices for any selected frequency range and thus makes possible a better frequency response and therefore greater bandwidth, especially at the higher microwave frequencies.

The foregoing and other aspects of this invention may be better understood from the following description of illustrative examples taken in connection with the accompanying drawings. The scope of the invention is defined by the appended claims.

In the drawings:

Fig. 1 is a somewhat schematic lengthwise section of an amplifier tube embodying principles of this invention; Fig. 2 is a transverse section taken generally along the line 2-2 of Fig. 1; and

Fig. 3 is a transverse section taken generally along the line 3-3 of Fig. 1.

Referring to the drawings, an evacuated metal envelope may consist of a hollow, non-circular cylindrical side portion 1 and two end plates 2 and 3, shaped and joined together as shown. An upper portion of the envelope serves as a collector electrode for the electron streams hereinafter described, and is provided with a plurality of cooling fins 4, 5, 6, 7 and 8 for dissipating the heat generated by electrons striking the envelope. Extending lengthwise within the evacuated envelope there are two parallel conductive helices 9 and 10 respectively wound upon and supported by strips of insulation 11 and 12.

The two helices are flattened in a vertical plane on each side so that when viewed from one end each helix has a narrow "race-track" shape, as shown in Figs. 2 and 3. If desired, for reducing dielectric loading of the helices or for other purposes, the sides of strips 11 and 12 may be recessed, or each strip of insulation may be replaced by two parallel non-conductive rods, to reduce the amount of dielectric material in immediate proximity to the flattened sides of the helices. Also, various other supporting structures may be substituted for strips 11 and 12 to support the helices within the envelope.

Each of the two helices is a slow-wave structure capable of transmitted electromagnetic waves with a phase velocity, in the direction of the helix axis, that is small compared to the velocity of light. The size and pitch of the helices are chosen in accordance with principles well-known to those skilled in the art to give optimum transmission characteristics in the frequency range at which the amplifier tube is designed to operate. In general, the helices will be made relatively large when optimum operation at relatively low microwave frequencies is desired, and will be made relatively small when operation in the higher microwave frequency ranges is required.

For any selected frequency range, especially in the higher microwave frequency ranges, helices 9 and 10 may be somewhat larger in cross-section than the helix in a conventional traveling-wave tube designed for operation in the same frequency range. The reason for this is that the avoidance of undesirable backward-wave oscillations imposes a major limitation upon the helix size in conventional traveling-wave tubes, as is well known. In tubes according to the present invention this limitation on the helix size can be disregarded and accordingly the helix can be made larger. This is an important advantage of the new tubes, because very small helices are dispersive, and this fact detracts from the frequency response of conventional traveling-wave tubes at the higher frequencies.

The left end of helix 9 (as viewed in Fig. 1) is connected or otherwise coupled to input terminals for receiving an electric signal that is to be amplified so that an input microwave signal can be introduced onto the left end of helix 9. For example, helix 9 may be directly connected as shown, or coupled by any of numerous microwave coupling arrangements known to those skilled in the art, to the center conductor 13 of a conventional coaxial cable connector that comprises, in addition to the center conductor 13, an outer conductor or shell 14 attached to and connected to the metal envelope of the tube, and a non-conductive vacuum seal 15. Thus, an input microwave signal can be supplied to input terminals 13 and 14 of the tube by a conventional coaxial cable (not shown) attached to the cable connector. Any input signal so introduced travels from left to right along the length of helix 9, with a phase velocity in the direction of the helix axis that depends chiefly upon the helix geometry and is small compared to the velocity of light. Because it transmits the input signal, helix 9 may be called the input helix.

The right end of helix 9 is provided with a low-reflection RF termination so that microwaves reflected at the right end of helix 9, and thereafter traveling from right to left toward the input terminals, will be substantially reduced in energy. A low-reflection termination for the helix can be provided easily by means of a conventional attenuator 16, which may be formed, for example, simply by spraying a thin coating of lossy conductive material (e.g., aquadag) on the right end of insulating strip 11 either before or after the helix is wound upon the insulating strip. A DC connection 17 between the right end of helix 9 and the metal envelope of the tube maintains helix 9 at substantially the same DC potential as the tube envelope, which is usually connected to circuit ground.

The right end of helix 10 (as viewed in Fig. 1) is connected or otherwise coupled to output terminals comprised in a conventional coaxial cable connector having a

center conductor 18 and an outer conductor or shell 19 that is attached to and connected to the metal envelope of the tube. Thus, electromagnetic waves transmitted from left to right along helix 10 are delivered to the output terminals, from which they may be transmitted through a conventional coaxial cable (not shown) attached to the cable connector. A low-reflection RF termination is provided at the left end of helix 10 by an attenuator 20 which may be similar in construction to attenuator 16. Thus, any wave components traveling from right to left along helix 10 are mostly absorbed by attenuator 20, and waves reflected at the left end of helix 10 are substantially reduced in energy. A DC connection 21 between the left end of helix 10 and the metal envelope of the tube maintains helix 10 at substantially the same DC potential as the tube envelope. Since helix 10 transmits signals to the output terminal it may be called the output helix. It will be noted that the principal microwave components transmitted by both helices travel in the same direction, from left to right as viewed in Fig. 1.

20 A conductive metal strip 22 extends lengthwise between and parallel to the input and output helices, as shown. Strip 22 is connected to the metal envelope of the tube and forms an RF shield and grounding strip that minimizes 25 direct electromagnetic coupling between the two helices. A conductive metal bar 23 connected to the metal envelope and disposed below and parallel to helix 9 also acts to some extent as an RF shield and grounding strip. In addition, bar 23 which is preferably made of 30 ferromagnetic material serves as a magnetic flux concentrator for purposes hereinafter explained, and serves as a first anode or accelerating electrode for the electron gun of the tube.

An elongated cathode 24 is heated by a conventional 35 heater filament 25 or by any other suitable means. A conventional oxide coating or the like, characterized by copious thermionic emission of electrons when heated, is coated in two long parallel strips 27 and 28 on the upper 40 surface of the cathode. Disposed above the cathode is a W-shaped focusing electrode 29 having lengthwise slots aligned over electron-emissive strips 27 and 28, as shown. The cathode, heater, and focusing electrode are supported at one end by pins embedded in an insulating base 30, and are supported at their other end by leads extending 45 through an insulating vacuum seal 31 in the tube envelope.

Current is supplied through the heater lead 32, connected to one end of filament 25, and another lead (not visible in the drawing) connected to the other end of filament 25, in a customary manner for heating the cathode sufficiently to produce thermionic emission of electrons by strips 27 and 28. A negative DC potential supplied through cathode lead 33 (by a conventional voltage supply, not shown) maintains the cathode at a negative potential relative to the metal envelope of the tube and bar 23. Consequently electrons emitted by the cathode are accelerated by the voltage between cathode 24 and bar 23, which acts together with the proximate portions of envelope 1 as a first anode or accelerating electrode of an electron gun, and flow to the upper part of the metal envelope, which acts as a collector electrode. A focusing potential is supplied through lead 26 to focusing electrode 29 by a conventional DC voltage supply, not shown. The value of this focusing potential may be adjusted in a well-known manner to focus the electrons emitted by strips 27 and 28 into two substantially planar and parallel sheets of electron flow that pass closely adjacent to opposite flat sides of helices 9 and 10. In Fig. 2 the boundaries of one sheet of electron flow are represented by broken lines 34 and 35, while the boundaries of the other sheet of electron flow are represented by broken lines 36 and 37. Similarly, in Fig. 3 the boundaries of the two sheets of electron flow are represented by broken lines 34', 35', 36' and 37'. In Fig. 1 broken lines 38 through 45 represent typical electron paths or rays in the sheet of electron flow emanating from strip 28.

In Fig. 1 it will be noted that the electron paths represented by broken lines 38 through 45 bend as they pass bar 23 so that the electrons flow past the input and output helices, successively, at an acute angle to the lengthwise axial direction of the helices. This bending of the electron paths is produced by a magnetic field supplied by a permanent magnet 46. Magnet 46 has two elongated poles that extend along opposite sides of the tube envelope, in approximately the positions shown in Fig. 2, for a distance somewhat greater than the width of the electron streams as viewed in Fig. 1. Magnet 46 provides a magnetic field that passes transversely through the tube, including that portion of ferromagnetic bar 23 lying between the two sheets of electron flow. Bar 23 is made of ferromagnetic material to concentrate the magnetic flux in a desired region of the electron streams. The tube envelope is generally not ferromagnetic but, if desired, it may have ferromagnetic inserts adjacent to the magnet pole pieces to assist in concentrating the magnetic flux.

As the electrons move through the magnetic field provided by magnet 46 and concentrated by bar 23 the electron paths are bent in a plane perpendicular to the field, according to well-known principles. The amount of bending, and therefore the angle between the electron paths and the axial direction of the helices, depends jointly upon the strength of the magnetic field and the electron velocities. The optimum magnetic field strength for a specific tube design can be determined from straightforward calculations, which will become obvious to those skilled in the art from an understanding of the principles disclosed in this specification.

In actual tube designs the magnetic field strength required to bend the electron beam as herein disclosed is usually small compared to the magnetic fields required for focusing a high-density electron beam in a conventional traveling-wave tube. Furthermore, in the present instance the flux lines are reasonably short and the reluctance of the magnetic circuit is relatively low, whereas in a conventional traveling-wave tube the flux lines are relatively long and the reluctance of the magnetic circuit is high. Consequently, the magnet required with the present tubes is small and inexpensive compared to the focusing magnets commonly used with conventional traveling-wave tubes.

There are two principal reasons why the electron paths in the tube under consideration are slanted with respect to the lengthwise axial direction of the helices. The electromagnetic waves transmitted by the helices have slow-wave components with phase velocities, in the lengthwise axial direction of the helices, that are small compared to the velocity of light. Therefore, these phase velocities are capable of being approximately matched by easily attainable electron velocities. With the slanting electron paths herein described, there is a component of electron velocity in the same direction as the aforesaid phase velocity of the microwaves transmitted on the helices. By adjusting the electron velocities, or the angle of the electron paths, or both, the component of electron velocity in the lengthwise axial direction of the helices can be made approximately equal to, and slightly greater than, the phase velocity in the same direction of a transmitted microwave component. This is the first reason for bending the electron paths.

After the electrons have been given a velocity component that approximately matches the aforesaid phase velocity, interactions of the traveling-wave amplifier type take place between the electron stream and the microwaves transmitted by each helix; provided that the interaction time (the time that each interacting electron, on the average, spends in the microwave fields) is sufficiently long. The length of the interaction region between each electron path or ray and the RF microwave field associated with each helix is a function of the angle between the electron paths and the lengthwise direction of the helix. If this angle were made very small, by using a strong enough magnet to bend the electron paths by al-

most 90 degrees, a long length of each electron path would be in a position to interact with the electromagnetic wave transmitted on one of the helices, the interaction time would be relatively large, and a correspondingly high degree of interaction would be obtained. With larger angles between the electron paths and the lengthwise direction of the helices the distance along each path wherein interaction can occur is shorter, the interaction time is reduced, and the total interaction between the electron stream and the electromagnetic waves is smaller. Thus, within reasonable limits any desired degree of interaction between the electron stream and the microwaves can be achieved by adjusting the direction of the electron paths relative to the helices. This is the second reason for bending the electron paths.

From the foregoing considerations it is apparent that each of the input and output helices, in association with the electron stream, is in some respects like the conventional traveling-wave amplifier. The electromagnetic wave transmitted along each helix interacts continuously with and may gain some energy from the electron stream, without regard to effects produced by the presence of the other helix.

There are also fundamental differences between the new tubes and conventional traveling-wave tubes. The electron stream can be thought of as being made up of many parallel rays, each representing an electron path. In a conventional traveling-wave amplifier substantially all of the rays pass in close interacting relation to substantially the entire length of a fairly long helix or other slow-wave structure. In other words, substantially the entire electron flow interacts with a transmitted electromagnetic wave over a fairly long distance and a considerable power gain can be realized with a single wave- transmission structure.

In tubes constructed according to the present invention each ray of the electron stream passes close to a relatively short lengthwise portion of each helix and interacts with a transmitted electromagnetic wave component over a correspondingly short distance. Other rays pass close to and interact with the electromagnetic wave components transmitted on other short lengthwise portions of each helix. Considering each of the two helices alone, and neglecting effects due to presence of the other, each helix in combination with the electron stream can be thought of as a plurality of very short traveling-wave amplifiers connected in series. Because of their short lengths, each of these hypothetical amplifiers has a low power gain. Preferably for broad-band amplification the length of each is made such (by adjusting the angle of the electron paths) that each hypothetical amplifier has approximately a unity microwave power gain—that is, the energy gained by the electromagnetic waves from interaction with the electron stream just balances circuit losses.

If each of the hypothetical short amplifiers operates at unity power gain then a plurality of such amplifiers connected in series must operate at unity power gain. An electromagnetic wave component introduced at any point along the helix. Thus, a signal supplied to the input terminals travels along the length of the input helix at a substantially constant energy level and equally modulates all transverse portions of the electron stream. Each wave component induced in any portion of the output helix (neglecting, for the moment, the components induced in other portions) is transmitted at a substantially constant energy level to the output terminals.

In such unity-gain structures self-sustained oscillations are impossible and backward-wave interactions present no difficulties, provided that a non-reflecting RF termination is provided at the beam entrance end of the wave-transmitting structure. In the embodiment illustrated, non-reflecting terminations are provided by the two attenuators 16 and 20, located at ends of the helices outside

of the region where interactions occur between the electromagnetic microwaves and the electron stream. There is no need for attenuation and attendant power losses in those portions of the helices where interactions with the electron stream occur. This in itself is a significant advantage over conventional traveling-wave tubes.

In actual practice adjusting the angle of the electron paths in the embodiment herein illustrated can be accomplished in a very simple manner. All that is necessary is to adjust the magnitude of the DC negative potential supplied to the cathode, thereby to adjust the electron velocities. Depending upon the strength and vertical thickness of the magnetic field a certain minimum electron velocity, and therefore a certain minimum accelerating voltage, is necessary to carry the electrons through the magnetic field and across the two helices. In other words, the total velocity imparted to the electrons by the accelerating voltage must exceed the horizontal component of velocity imparted to the electrons by their passage through the magnetic field so that there will be a remaining vertical component of velocity sufficient to carry the electrons transversely across the two helices in succession. As the electron velocity is increased beyond this minimum value, by making the cathode more negative relative to the tube envelope, the angle between the electron paths and the lengthwise direction of the helices increases, and the length of each path that can provide interactions with the microwave fields, and therefore the interaction time, decreases.

The horizontal velocity component of the electron flow, in a direction parallel to the longitudinal axes of the helices, is chiefly determined by the magnetic field and is but slightly if at all affected by moderate changes in the total electron velocity. Consequently, once the magnetic field strength is established at the proper value to create in the electron flow a horizontal velocity component that is approximately equal to, and slightly greater than, the horizontal phase velocity of an electromagnetic wave component transmitted by the helices, this essential velocity relationship continues substantially unaltered while the total electron velocity is adjusted by varying the cathode potential to adjust the angle of the electron paths, thereby to adjust the degree of traveling-wave amplifier action that can take place in each helix independently of the other.

Since the horizontal component of velocity that is imparted to the electrons by their passage through the magnetic field is proportional to the magnetic field strength, the phase-positional relation necessary for traveling-wave interaction between the microwave fields and the electron stream is achieved simply by adjusting the magnetic field strength. This adjustment preferably is made during manufacture of the tube by adjusting the strength of permanent magnet 46 but, if desired, means for adjusting the magnetic field strength during use of the tube can be provided either by substituting an electromagnet for the permanent magnet or by providing a magnetic shunt or the like for adjusting the effective strength of the permanent magnet.

While each of the two helices in association with the electron stream is in itself, without the other, a traveling-wave amplifier, preferably having a power gain of approximately unity, the two helices and the electron stream in combination, according to the principles and examples herein set forth, constitute a microwave power amplifier operable at high gain and large microwave output power, with efficiencies appreciably higher than those previously attained with broad-band amplifiers at microwave frequencies. As the input signal travels along the input helix it velocity-modulates successive transverse portions of the electron stream. The velocity-modulation causes some degree of bunching in the electron stream as it flows toward the output helix. Each transverse portion of the bunched stream transfers energy to a different

lengthwise portion of the output helix, establishing there-in electromagnetic wave components that travel along the output helix and arrive at the output terminals in additive phase relation.

5 The achievement of high efficiency requires that as large a proportion as possible of the kinetic energy of the electron stream be converted into microwave electromagnetic energy. Tubes constructed according to the present invention are capable of accomplishing this conversion to a greater degree than has been achieved in conventional traveling-wave tubes and therefore the new tubes are more efficient power amplifiers.

10 For purposes of analysis, assume that the two sheets of electron flow are broken up into separate parallel 15 electron beams and that each of the broken lines 38 through 45 in Fig. 1 represents a separate electron beam. The input signal traveling from left to right on input helix 9 velocity-modulates each of these electron beams by substantially equal amounts. Furthermore, the modulation 20 of beam 39 is delayed with respect to the modulation of beam 38 by the time interval required for the input wave to travel along the input helix in the direction of the helix axis a distance equal to the spacing between beams 38 and 39, and the modulation of each following 25 beam is likewise delayed with respect to the preceding beam.

30 A certain amount of electron bunching occurs in each of the velocity-modulated beams as it travels between the input and output helices. As beam 38 passes adjacent to 35 output helix 10 it induces on the output helix an electromagnetic microwave component that travels from left to right toward the output terminals. The amplitude of this induced signal component may be quite small and its RF field correspondingly weak. Because it is interacting with a weak RF field only a small proportion of the kinetic energy of beam 38 is converted into microwave electromagnetic energy. Therefore, the power efficiency associated with beam 38 is low.

40 Beam 39 induces another microwave component on 45 output helix 10. However, since the modulation of beam 39 is delayed with respect to the modulation of beam 38 by the time interval required for a microwave to travel along one of the helices a distance equal to the spacing between the beams, the wave component induced on helix 10 by beam 38 arrives at that portion of the output 50 helix interacting with beam 39 at just the right time to be in additive phase relation to the wave component induced on helix 10 by beam 39. Consequently, the two 55 wave components reinforce each other, and produce a correspondingly stronger RF field interacting with beam 39. This stronger RF field extracts more energy from beam 39 than was extracted from beam 38, and therefore beam 39 loses a larger proportion of its kinetic energy to the RF field. Thus, the power efficiency associated with beam 39 is higher than the power efficiency associated with beam 38.

60 In like manner each succeeding one of the electron beams interacts with a stronger RF field on helix 10 and therefore transfers a greater proportion of its kinetic energy to the electromagnetic wave traveling along the helix. Thus, the efficiency associated with each succeeding electron beam is somewhat higher than the efficiency associated with the preceding beam.

65 Things continue in this way until saturation effects set in. Eventually the RF field traveling along helix 10 becomes strong enough at its cyclical peaks to stop the horizontal motion of the electrons. Upon any further increase in the field strength other factors remaining unchanged, the motion of at least some electrons would be reversed—that is, these electrons would be accelerated by the RF field and move toward the left of Fig. 1. If this saturation condition were substantially exceeded the interaction of each succeeding electron beam would tend to be less efficient, instead of more efficient, than that of the preceding beam. This difficulty can be overcome and

still higher power output and higher efficiency achieved, as will now be explained.

Assume that saturation conditions, as above described, are first encountered at electron beam 42. To be more precise, assume that beam 42 encounters an RF field of such strength that maximum efficiency is associated with beam 42, and any greater interaction between an electron beam and the RF field would lower the efficiency. Since the electromagnetic wave is increasing in energy as it travels from left to right on helix 10 the RF field on that portion of helix 10 adjacent to beam 43 is stronger than the RF field adjacent to beam 42. However, the RF field strength falls off rapidly with increasing distance away from the helix. Therefore, if beam 43 is tilted outward away from helix 10 slightly so that it does not pass as close to the helix as beam 42, beam 43 can be made to pass through an RF field of substantially the same strength as the RF field that beam 42 encounters, and therefore both of the beams 42 and 43 will transfer maximum energy to the electromagnetic wave.

Similarly, beam 44 will be tilted outward away from helix 10 slightly more than beam 43, and beam 45 will be tilted outward still more. By this means each beam to the right of beam 41 can be made to transfer maximum energy to the microwave field and the over-all efficiency of the tube asymptotically approaches the theoretical maximum as the length of the tube is increased. Furthermore, this is accomplished without tapering the electrical characteristics of the helices, so that uniformly wound helices can be employed, which is a substantial advantage in tube manufacture.

Where the electron flow takes the form of continuous sheets rather than discrete beams as it does in the embodiment illustrated, each transverse portion of the sheet follows the same path that it would follow if it were a separate beam. In other words, the respective planes of the two sheets of electron flow in the embodiment illustrated are slightly warped so that the two sheets of electrons are parallel and pass as close as possible to both helices (as illustrated in Fig. 2) toward the left end of the tube as viewed in Fig. 1 and are slightly tilted apart (as illustrated in Fig. 3) toward the right end of the tube. This tilting of the electron stream is easily accomplished by a slight bending of the focusing electrode 29, as is illustrated in Fig. 3 of the drawings.

A considerable gain in efficiency is accomplished by the means discussed above. If the length of the tube were terminated at the point where maximum beam efficiency is first obtained, or if the tube were continued beyond this length without some form of compensation for the saturation effects, only one of many parallel electron beams, or a corresponding portion of an electron sheet, could deliver maximum energy to the electromagnetic waves on the output helix. Under such circumstances, the over-all efficiency would be comparatively low because of the relatively large number of beams or equivalent portions of a sheet operating at low efficiencies. By extending the length of the tube and compensating for saturation effects in the manner herein disclosed, the number of high-efficiency beams or equivalent sections of an electron sheet can be increased without increasing the number of low-efficiency beams and therefore the over-all efficiency can be raised considerably. High efficiencies in the order of those obtainable with narrow-band amplifiers, such as klystrons, are thus obtainable in an amplifier capable of exceptionally broad-band operation.

Numerous variations in tube structure can be made while utilizing some or all of the inventive principles herein disclosed. For example, in the preceding description it was assumed for illustrative purposes that each of the broken lines 38 through 45 represented a separate electron beam rather than a typical electron path in a continuous sheet of electron flow. In fact, a tube can be built along these lines utilizing a plurality of separate conventional electron guns with small-area cathodes each supplying one of the several electron beams. These elec-

tron guns may be oriented in the desired direction of electron flow, at an acute angle to the lengthwise axial direction of the two helices. The magnet for bending the electron beam then becomes unnecessary. Such a modification may be quite attractive for moderate output power applications. For achieving high output power as well as achieving certain other advantages the illustrated embodiment appears preferable at present.

In another modification, an elongated strip cathode like that illustrated in Fig. 1 may be employed, but magnet 46 omitted, so that substantially parallel sheets of electrons flow past opposite sides of the two helices perpendicular to the lengthwise direction of the tube. In this embodiment the helices are skewed—that is, each helix turn extends down one side of the insulating strip with a relatively small slope in a left-to-right direction and back up the other side of the insulating strip with a slightly greater slope in a right-to-left direction. By this means the wave fronts of the transmitted microwaves are slanted relative to the electron flow, instead of slanting the electron flow relative to the wave fronts. A difficulty with this arrangement is that the interaction time is likely to be low unless a very large helix is used. But a very large helix transmits microwaves with a low phase velocity and therefore requires a low-velocity electron stream, which limits the output power that can be obtained.

According to a still another modification, each helix may be physically divided into a plurality of short helical sections electrically connected in series and each section of the subdivided helix is then turned by 90 degrees from the orientation of the helices illustrated in the drawing. In other words, the horizontal input helix 9 (illustrated in Fig. 1) would be subdivided into a plurality of vertically disposed short helical sections arranged in a horizontal row and electrically connected in series. Similarly, output helix 10 would be divided into a plurality of vertically disposed helical sections arranged in a horizontal row and each vertically disposed section of helix 10 would be vertically aligned with a vertically disposed section of helix 9.

An electron beam is then provided in interacting relation with each pair of vertically aligned helix sections. That is, one electron beam would pass through a first short section of helix 9 and a first short section of helix 10 in sequence, another electron beam would pass through a second short section of helix 9 and a second short section of helix 10 in sequence, etc. Preferably, each helix section in association with an electron beam would be of an appropriate length to yield a traveling-wave power gain of approximately unity, so that input signals would travel from one section to the next of the input structure at a substantially constant power level and any signal component induced in the output structure would travel to output terminals at a substantially constant power level. Each electron beam and associated pair of short helix sections forms a low-gain amplifier section but the signals produced in the output circuit of each such amplifier section combine in additive phase relation with signals produced in the output circuits of the other amplifier sections to provide a substantial power gain in the over-all structure.

Numerous other changes and modifications will occur to those skilled in the art. In some applications other slow-wave structures may be found to be equally suitable or even preferable to helices. In general, however, it appears at present that helices are the preferred slow-wave structures for broad-band amplification.

The tilting of the electron sheets to compensate for saturation effects, as herein described, is not essential to other aspects of this invention and may be omitted where the utmost improvement in efficiency is not required. In some cases other compensating means may be employed, such as winding helix 10 non-uniformly to provide a decreasing helix impedance from left to right but

in general this is less advantageous than the preferred means herein described because of manufacturing difficulties and other reasons.

The tubes herein described are easily distinguishable from prior well-known microwave amplifiers as well as from certain unsuccessful proposals made in the past. The new tubes are believed to be a new type of microwave amplifier in the traveling-wave family.

Traveling-wave tubes using a sheet-like electron flow across a skewed helix have been proposed previously. The present tubes are fundamentally different from such prior tubes since in the present tubes, when operated as broad-band amplifiers in the preferred manner herein disclosed, no attempt is made to secure much gain from a transverse beam interacting with a single helix. In the present tube broad-band amplification is achieved through successive interactions with two separate slow-wave structures.

Tubes have previously been proposed and sometimes called traveling-wave tubes wherein a sheet of electrons flows through elongated interaction gaps in input and output waveguides successively. However, according to such prior proposals the interaction between the electromagnetic waves and the electron stream occurs in klystron-like fashion across a single interaction gap in each waveguide. The present tubes are fundamentally different from such prior proposals in that the interaction between the electron stream and each electromagnetic wave occurs over an interaction distance of several wavelengths, with a corresponding long interaction time, in accordance with traveling-wave amplifier principles. Consequently, the interactions that occur in the present tubes are of a different degree of magnitude from those occurring across the single gap of the aforesaid klystron-like prior art proposals and a fundamentally different type of operation is obtained with totally different end results.

Furthermore, the present tubes are not distributed amplifiers which utilize control grids and space-charge effects as the primary means for modulating the electron flow. In the present tubes control grids may be incorporated in the electron guns for auxiliary purposes as they are in conventional traveling-wave tubes but such control grids are not the primary, nor even a necessary, means for modulating the electron stream at microwave frequencies. Modulation of the electron stream and the extraction of energy therefrom both proceed according to the traveling-wave amplifier principle as herein explained.

Nor are the present tubes magnetrons which have crossed electric and magnetic fields in the interaction regions. The present tubes may use magnetic fields for beam-focusing purposes or for bending the beam trajectories in the manner herein explained but interaction between the electron stream and the electromagnetic waves does not occur in crossed static electric and magnetic fields of the magnetron type.

Amplifier tubes embodying principles of this invention and in particular the preferred embodiment illustrated in the accompanying drawings may be connected in a variety of circuits for various purposes. Connections for operating the tube illustrated as a broad-band microwave amplifier have already been described in this specification. Many other connections and modes of operation will be apparent to those skilled in the art. For example, a microwave oscillator can be formed by providing a conventional regenerative feedback circuit between the output and input terminals of the tube. Also, various means may be employed to modulate the microwave signals which means may or may not include modifications or additions to the internal structure of the tube, such as the provision of one or more additional electrodes in the electron gun for varying the electron current in the electron stream.

The illustrated embodiment wherein a magnetic field is used to bend the electron paths has certain unusual characteristics that are of particular interest with respect

to the use of the tube as a modulator. As hereinbefore noted the phase-positional relation between the microwave traveling on the two helices and the moving electrons in the electron stream is established by the strength and vertical thickness of the magnetic field and is substantially independent, within reasonable limits, of the total velocity imparted to the electrons by the accelerating voltage. On the other hand, the interaction time and thus the degree of interaction between the traveling microwaves and the electron stream may vary considerably with moderate changes in the magnitude of the accelerating voltage. Therefore, in contrast to conventional traveling-wave tubes the tube illustrated permits substantially independent adjustment of the aforesaid phase-positional relation and the interaction impedance of the tube, in a simple and convenient manner while the tube is in operation if such is desired.

For example, assume that an alternating modulating voltage is applied to cathode 24 in addition to the normal DC accelerating potential. The modulating voltage will have little if any effect on the horizontal component of velocity of the electrons in the bent electron paths and thus will have little if any effect upon the phase-positional relation between the traveling microwaves and the moving electrons. Thus, the modulating voltage does not appreciably affect the frequency response of the tube, whether it is being used as an amplifier or as an oscillator, or for other purposes. The alternating modulating voltage does produce a periodic variation in the angle between the bent electron paths and the longitudinal axial direction of the helices and this produces a periodic variation in the microwave power gain of the tube which amplitude-modulates the microwave power delivered at the output terminals.

For broad-band amplification the magnitude of the accelerating voltage preferably is adjusted to give approximately unity power gain in the traveling-wave amplifier action associated with each helix independently of the other, as hereinbefore explained. In narrow-band and signal-generator applications this is not necessarily the case. For example, assume that the accelerating voltage (between cathode 24 and the tube envelope) is adjusted to a value just slightly greater than the minimum value required to carry the electrons through the magnetic field so that the electron paths cross the two helices at a small acute angle to the longitudinal axial direction of the helices. Under these conditions the power gain arising from the traveling-wave amplifier action associated with each helix, independently of the other, may become sufficiently greater than unity that sustained backward-wave oscillations are generated on input helix 9. Thus, microwave oscillations can be generated without resort to external feedback circuits and microwave energy can be withdrawn either from terminals 13 and 14 at the left end 55 of helix 9, or from terminals suitably coupled to helix 10. When the output energy is withdrawn directly from helix 9, helix 10 may be omitted. When the output energy is withdrawn from helix 10 an electron-coupled backward-wave oscillator is provided. In both cases the novel backward-wave oscillators can be tuned by adjusting the magnetic field strength, and can be amplitude-modulated by adding an alternating modulating voltage to the DC accelerating voltage.

If the accelerating voltage is adjusted to a value slightly above the highest value that produces sustained oscillations a narrow-band amplifier of exceptionally high gain can be provided. Input signals are supplied to the left end of helix 9 and output signals can be withdrawn from the right end of either helix. Such an amplifier may also be useful as a microwave negative resistance.

It should be understood that this invention in its broader aspects is not limited to specific examples herein illustrated and described, and that the following claims are intended to cover all changes and modifications within the true spirit and scope of the invention.

What is claimed is:

1. A traveling-wave tube comprising the following combination: means enclosing an evacuated space; two substantially parallel coextensive slow-wave structures electromagnetically isolated from each other and each adapted to transmit an electromagnetic wave component with the phase velocity that is small compared to the velocity of light; and means for providing within said evacuated space an electron stream flowing closely across said two slow-wave structures in sequence, said stream having a velocity component in the same direction as and approximately equal to said phase velocity, whereby low-gain interactions of the traveling-wave amplifier type occur between said stream and electromagnetic waves on each of said slow-wave structures while high-gain interactions occur between waves on respective ones of said structures through modulation of the electron stream.

2. A traveling-wave amplifier tube comprising the following combination: means enclosing an evacuated space; first and second slow-wave structures within said space electromagnetically isolated from each other and each consisting essentially of a plurality of conductive helical sections coupled together in series, each of said helical sections being adapted to transmit an electromagnetic wave component with a phase velocity smaller than the velocity of light; means for providing within said evacuated space an electron stream flowing closely by said first and second slow-wave structures in sequence, said stream including a plurality of portions respectively following parallel electron paths each passing close to substantially only one of said helical sections of each slow-wave structure; coupling means for supplying microwave signals to said first slow-wave structure, said signals traveling along said first structure from one helical section to another for modulating the several portions of said stream successively, the so-modulated portions of said stream inducing microwave components in respective helical sections of said second slow-wave structure, the so-induced components traveling along said second structure from one helical section to another and combining with one another in additive phase relation, whereby an amplified microwave signal is produced on said second slow-wave structure; and coupling means for extracting said amplified signal from said second slow-wave structure.

3. A traveling-wave amplifier tube comprising the following combination: means enclosing an evacuated space; first and second conductive helices electromagnetically isolated from each other and extending substantially parallel to each other within said space, each of said helices being adapted to transmit microwave electromagnetic field components with moving wavefronts traveling slower than the velocity of light; means for providing within said evacuated space an electron stream flowing successively through the electromagnetic fields transmitted by said first helix and the electromagnetic fields transmitted by said second helix, said stream having a velocity component perpendicular to said wavefronts and approximately equal to the velocity of said wavefronts in the same direction so that electrons in said stream pass through each of said fields in approximately constant phase-positional relation thereto; input coupling means for supplying input microwave signals to one end of said first helix, said input signals traveling along said first helix and successively modulating different portions of said stream, the so-modulated electron stream inducing output microwave signals on said second helix; and output coupling means for extracting said output signals from the end of said second helix that is most distant from said input coupling means.

4. A traveling-wave tube comprising the following combination: means enclosing an evacuated space; first and second helices disposed in laterally spaced relation within said space, with the longitudinal axes of said helices substantially parallel, each of said helices being a separate slow-wave structure adapted to transmit traveling elec-

tromagnetic waves with a phase velocity in the longitudinal axial direction of the helix that is small compared to the velocity of light; means for providing within said space an electron stream flowing closely across said first and second helices successively, the direction of electron flow in said stream being at an acute angle to the longitudinal axial direction of said helices, and the velocity of said flow being such that said stream has a velocity component in the direction of and approximately equal to said phase velocity, whereby interactions occur between said stream and said electromagnetic waves on each helix such that the waves on said first helix modulate said stream and the so-modulated stream induces amplified waves on said second helix.

5. A traveling-wave tube comprising the following combination: means enclosing an evacuated space; an elongated slow-wave structure adapted to transmit electromagnetic wave components in a longitudinal direction within said evacuated space at a phase velocity that is small compared to the velocity of light; an electron-emissive cathode disposed within said evacuated space; electrode means for accelerating electrons emitted by said cathode into a stream of electrons flowing closely across said slow-wave structure, the initial direction of said flow being substantially perpendicular to said longitudinal direction, and magnet means for producing a transverse magnetic field extending perpendicularly through said stream of electrons between said cathode and said slow-wave structure, the strength of said field having a predetermined value so as to cause said electrons to follow bent paths and to flow across said slow-wave structure substantially outside of said magnetic field along straight-line paths disposed at an acute angle to said longitudinal direction, the strength of said magnetic field further being such that said electrons as they pass said slow-wave structure have a velocity component in the same direction as and substantially equal to said phase velocity, whereby interactions of the traveling-wave amplifier type occur between said electrons and said electromagnetic wave components.

20 6. A traveling-wave amplifier tube comprising the following combination: means enclosing an evacuated space; first and second elongated conductive helices disposed in laterally spaced relation within said space with the longitudinal axes of said helices substantially parallel, said helices having sides flattened in a common plane, each of said helices being a separate slow-wave structure adapted to transmit traveling electromagnetic waves with a phase velocity in the longitudinal axial direction of the helices that is small compared to the velocity of light, an electron-emissive strip cathode disposed within said evacuated space substantially parallel to the longitudinal axes of said helices; electrode means for accelerating electrons emitted by said cathode into a sheet of electrons flowing closely across a flattened side of said first helix and a flattened side of said second helix in succession; magnet means having elongated pole pieces of opposite polarity disposed on opposite sides of said sheet of electrons and extending substantially parallel to the longitudinal axes of said helices, said magnet means providing a magnetic field that extends perpendicularly through substantially the entire width of said sheet of electrons in a region between said cathode and said first helix, whereby said electrons follow bent paths and flow across said two helices outside of said magnetic field along substantially straight paths disposed at an acute angle to the longitudinal axial direction of the helices, the strength of said magnetic field being such that said electrons have a velocity component in the same direction as and substantially equal to said phase velocity, whereby low-gain interactions of the traveling-wave amplifier type occur between said electrons and each of the electromagnetic waves transmitted by respective ones of said helices, while high-gain interactions occur between the waves transmitted by respective ones of said helices through modulation of the electron flow; input connections for supplying electromagnetic waves to

25 30 35 40 45 50 55 60 65 70 75

one end of said first helix; attenuator means providing a low-reflection microwave termination at the other end of said first helix; attenuator means providing a low-reflection microwave termination at the end of said second helix nearest said input connections; and output connections for withdrawing electromagnetic waves on the other end of said second helix.

7. A traveling-wave amplifier tube comprising the following combination: means enclosing an evacuated space; two substantially parallel elongated slow-wave structures each adapted to transmit an electromagnetic wave component in the lengthwise direction of said structures with a phase velocity that is small compared to the velocity of light; means for providing within said evacuated space an electron stream flowing closely across said two slow-wave structures in sequence at an acute angle to the lengthwise direction of said structures, said stream having a velocity component in the same direction as and approximately equal to said phase velocity, whereby low-gain interactions of the traveling-wave amplifier type occur between said stream and electromagnetic waves on each of said low-wave structures considered independently of the other, said acute angle being so chosen that said low-gain interaction produces approximately unity power gain; input connections for supplying microwave signals to one end of the one of said two slow-wave structures that said electron stream flows across first, said microwave signals traveling along the length of that slow-wave structure and velocity-modulating different portions of said electron stream successively, the so-modulated stream inducing microwave signal components on different lengthwise portions of the other of said two slow-wave structures that travel along said other structure and combine in additive phase relation, whereby an amplified microwave signal is produced on said other structure for realizing a high power gain; and output connections for withdrawing said amplified signal from said other slow-wave structure.

8. A traveling-wave amplifier tube comprising the following combination: means enclosing an evacuated space; two substantially parallel elongated slow-wave structures each adapted to transmit an electromagnetic wave component in the lengthwise direction of said structures with

a phase velocity that is small compared to the velocity of light, means for providing within said evacuated space an electron stream flowing closely across said two slow-wave structures in sequence, said stream having a velocity component in the same direction as and approximately equal to said phase velocity, whereby low-gain interactions of the traveling-wave amplifier type occur between said stream and electromagnetic waves on each of said slow-wave structures; input connections for supplying input microwave signals to one end of the one of said two slow-wave structures that said electron stream flows across first; and output connections for withdrawing output electric signals from the other end of the other of said two slow-wave structures; said input signals traveling along the length of said one slow-wave structure and velocity-modulating successive portions of said electron stream successively, the so-modulated stream inducing microwave signal components in successive portions of said other slow-wave structure, the so-induced components traveling along said other structure toward said output connections and combining with each other in additive phase relation to produce a growing wave that increases in energy as it travels along said other structure, said electron stream clearing said other structure by an amount that increases progressively toward said output connection to prevent over-saturated interaction between the growing wave and the electron stream.
